LIPSTICK CASE OR SIMILAR ARTICLE

Frederick M. Breen, White Plains, N. Y., assignor to Coty, Inc., New York, N. Y., a corporation of Delaware

Application January 25, 1955, Serial No. 34,201

Term of patent 14 years

(Cl. D86—10)

Fig. 1.

Fig. 2.

Fig. 3.

Fig. 1 is a front elevational view of a lipstick case or similar article, showing my new design;

Fig. 2 is a top plan view; and

Fig. 3 is a bottom plan view.

The drawing has been shaded to show contrasting appearances. The design is characterized by the beveled beaded elements in relation to and in association with the contrasting bands at the end portions.

I claim:

The ornamental design for a lipstick case or similar article, substantially as shown and described.
